United States Patent Office

Des. 185,415
Patented June 9, 1959

185,415

ACTION TOY

Walter P. Doe and Ralph W. Crawford, East Aurora,
N.Y., assignors to Fisher Price Toys, Inc., East Aurora,
N.Y.

Application January 15, 1958, Serial No. 49,261

Term of patent 14 years

(Cl. D34—15)

Fig. 1.

Fig. 2.

Fig. 1 is a top plan view of an action toy, showing our new design; and

Fig. 2 is a side elevational view thereof.

The fragmentary broken line showing of a pull string is for illustrative purposes only.

We claim:

The ornamental design for an action toy, substantially as shown and described.
